UNITED STATES PATENT OFFICE.

GEORGE H. BURROWS, OF SOMERVILLE, MASSACHUSETTS.

STOCKLESS ANCHOR.

SPECIFICATION forming part of Letters Patent No. 605,076, dated June 7, 1898.

Application filed August 17, 1897. Serial No. 648,525. (No model.)

To all whom it may concern:

Be it known that I, GEORGE H. BURROWS, a citizen of the United States, residing at East Somerville, in the county of Middlesex and 5 State of Massachusetts, have invented certain new and useful Improvements in Stockless Anchors; and I do declare the following to be a full, clear, and exact description of the invention, such as will enable others skilled in 10 the art to which it appertains to make and use the same.

My invention relates to stockless anchors; and the object is to provide a simple, cheap, and effective device of this kind.

15 To this end the invention consists in the construction, combination, and arrangement of the device, as will be hereinafter more fully described, and particularly pointed out in the claims.

20 In the accompanying drawings the same reference characters indicate the same parts of the invention.

Figure 1 is a perspective view of my improved stockless anchor. Fig. 2 is a horizontal section with the flukes alined with the shank. Fig. 3 is a longitudinal section of the same. Fig. 4 is a similar view showing the manner of securing the shank in the flukes when the shackling-pin is removed.

30 1 represents the rectangular shank, which is provided with the usual shackle 2, and its outer end is formed with an integral T-shaped head 3, having lateral lugs 4 4 and a transverse orifice 5 for the reception of the shackling-pin.

35 6 represents the crown formed with the parallel flukes 7 7, which extend rearwardly in the same plane and on opposite sides of the shank.

40 8 represents a longitudinal rectangular orifice extending through the crown to receive the shank, which is pivoted therein by the shackling - pin 9, extending transversely through the orifice 10 in said crown and the 45 alined orifice 5 in the shank.

The orifice 8 is formed with parallel walls 11 11 and rearwardly-diverging walls 12 12, formed at an angle of about ninety degrees, which allow the flukes to have a movement 50 of about forty degrees on either side of the shank when the anchor is in service. Each of the parallel walls 11 11 is formed with a

V-shaped recess 15 to receive the corresponding lugs 4 4 on the T-shaped head of the shank, so that should the shackling-pin become accidentally detached or break the lugs on the shank will engage the upper ends of the recesses in the crown and thereby hold the shank in place as securely as in the first instance.

55 13 and 14 represent integral lateral arms projecting centrally on opposite sides of the crown, the office of which, in addition to forming sockets for the outer end of the shank, also serves to throw the crown up and the 60 bills of the flukes downward, so as to facilitate their engagement with the ground when the anchor has been cast overboard.

65 Among the various advantages possessed by an anchor of this construction may be noted 70 the following: Both flukes take hold simultaneously, and it therefore has double the power over the ordinary form, in which only one fluke takes hold in the ground.

The absence of the stock prevents the possibility of fouling the cable when the vessel 75 is lying at anchor, and owing to the absence of the stock can be housed in much less space.

Again, the shank may follow the cable 80 through the hawse-hole and the crown drawn taut against the hawse-plate, thus saving the troublesome work of cutting and lashing the anchor. When the anchor is in use, both flukes are embedded in the ground. Consequently there is no obstruction projecting 85 above the crown for the cable to twist around. when the vessel is swinging with the tide, and, in fact, the pin 9 may be dispensed with in practice without in any manner interfering with the utility or effectiveness of the an- 90 chor while in service.

Again, if the shackling-pin should break the T-shaped head is still pivotally secured in the crown as firmly as if the shackling-pin 95 was in place.

Although I have specifically described the construction and relative arrangement of the several elements of my invention, I do not desire to be confined to the same, as such changes or modifications may be made as 100 clearly fall within the scope of my invention without departing from the spirit thereof.

Having thus fully described my invention, what I claim as new and useful, and desire to

secure by Letters Patent of the United States, is—

- 5 1. An anchor comprising the crown 6, formed with the integral parallel and rearwardly-extending flukes 7 7, and the longitudinal rectangular orifice 8, formed between the parallel walls 11, 11, and having V-shaped recesses formed in their opposite faces, in combination with the rectangular shank 1, 10 provided with the T-shaped head 3, having lateral lugs 4 4, adapted to engage said V-shaped recesses, substantially as shown and described.
2. An anchor comprising the crown, the

flukes, the shank, and the shackling-pin, the 15 crown having a central aperture formed with stop-shoulders and the shank having a head pivoted in said aperture at the rear of the stop-shoulders by said shackling-pin, whereby, should the shackling-pin break, the head 20 will engage said shoulders and prevent the parts separating.

In testimony whereof I hereunto affix my signature in presence of two witnesses.

GEORGE H. BURROWS.
